UNITED STATES PATENT OFFICE.

RICHARD KALLMAN, OF DAVENPORT, IOWA.

DEVICE FOR HANDLING BAKING-PANS.

1,031,649.

Specification of Letters Patent.

Patented July 2, 1912.

Application filed December 28, 1911. Serial No. 668,299.

To all whom it may concern:

Be it known that I, RICHARD KALLMAN, a citizen of the United States, residing at Davenport, in the county of Scott and State 5 of Iowa, have invented certain new and useful Improvements in Devices for Handling Baking-Pans, of which the following is a specification, reference being had therein to the accompanying drawing.

10 This invention relates to pan lifters and the principal object of the same is to improve and simplify the construction of devices of this character and provide, as a new article of manufacture, a pan lifter formed 15 entirely from wire.

With the above and other objects in view the invention consists in general of certain novel constructions, arrangements and combinations of parts as will be hereinafter 20 fully described, illustrated in the accompanying drawings and specifically claimed.

In the accompanying drawings like characters of reference indicate like parts in the several views, and:—Figure 1 is a perspective view showing the manner of using the device. Fig. 2 is a partial detail showing the manner in which one of the members 25 engages beneath the edge of a pan.

This invention consists of two parts, one 30 whereof is adjustably mounted upon the other to accommodate different sized pans, and the like. The first of these parts consists of a single length of wire bent intermediate its ends to form a loop 10. The 35 wire is then twisted together to form what may be termed the core of the handle as indicated at 11 and this twisting is carried down to a point 12 where the wires diverge into branches 13. Each of these branches 40 is bent downwardly as at 14 and again upwardly as at 15, the bight portion 16 thus formed being bent under to constitute a gripping claw. From the upper end of each portion 15 the wire is led back as at 17, 45 these parts being substantially parallel and is repeatedly bent into a series of loops 18 spaced along the portion 17 and opposite each other. From the last loop 18 the wire is bent directly in toward the handle as indicated at

19 and the two ends are then twisted around 50 the core 11 so that they lie in the grooves of the twist of said core as indicated at 20, terminating adjacent the loop 10 as at 21. The other member consists of a single length of wire bent to form an arcuate portion 55 22 intermediate its ends. From this arcuate portion lateral portions extend as at 23 which terminate in upwardly extending portions 24. The wire ends are then led parallel to each other as at 25 and inturned 60 as at 26, the portions 26 being held in a suitable pair of the loops 18 as can readily be seen by reference to Fig. 1.

The wire used in the construction of this 65 invention is resilient and by reason of this the arms 25 may be forced apart so that the ends 26 may be inserted in any pair of the loops at will, thus making the device adjustable to any sized pan, as can readily be understood from an inspection of Fig. 1. 70

In using the device the handle is grasped in such manner that the portion 22 hangs down. It is then placed in the oven so that 75 22 catches in one edge of the pan and the ends 16 are pushed forward until they engage over the other edge of the pan. By lifting the handle the end 16 and portion 22 will be drawn toward each other until the pan is firmly grasped by the device. It then may be lifted from the stove without 80 any danger of burning the hands. There has thus been provided a simple and efficient device of the kind described and for the purpose specified.

Having thus described the invention, what 85 is claimed as new, is:—

As a new article of manufacture, a pan lifter consisting of two lengths of wire being bent intermediate its ends to form a 90 loop, twisted from the loop to form a handle core, provided at the end of the twist with diverging portions terminating in downwardly and upwardly bent portions, the bights formed by said bends being bent under, straight portions leading from the 95 upwardly bent portions and provided with a series of spaced loops, inwardly directed portions extending from adjacent the last

loops, and terminal portions twisted around the handle core and lying in the grooves of the twist of said handle to strengthen said handle, the other of said lengths of wire being arcuately bent intermediate its ends, then 5 bent outwardly at each end of the arc, then bent upwardly and inwardly, and terminating in opposed inturned ends adapted

to be received in selective loops of the series of loops of the first length of wire.

In testimony whereof I hereunto affix my signature in presence of two witnesses.

RICHARD KALLMAN.
